CLAIM

The ornamental design for a surface pattern applied to a television set, as shown and described.

DESCRIPTION

FIG. 1. is a perspective view thereof;

FIG. 2. is a front elevational view thereof;

FIG. 3. is a rear elevational view thereof;

FIG. 4. is a left side elevational view thereof;

FIG. 5. is a right side elevational view thereof;

FIG. 6. is a top plane view thereof; and,

FIG. 7. is a bottom plane view thereof.

The broken line showing of a television is included for the purpose of illustrating environmental structure and forms no part of the claimed design.
